UNITED STATES PATENT OFFICE.

OSCAR TOWER, OF KENMORE, NEW YORK, ASSIGNOR OF ONE-HALF TO FRANK E. BLAKESLEE, OF BUFFALO, NEW YORK.

RAILWAY-CAR DOOR.

No. 870,062.

Specification of Letters Patent.

Patented Nov. 5, 1907.

Application filed February 4, 1907. Serial No. 355,553.

To all whom it may concern:

Be it known that I, OSCAR TOWER, a citizen of the United States, residing at Kenmore, in the county of Erie and State of New York, have invented a new and useful Improvement in Railway-Car Doors, of which the following is a specification.

This invention relates to a door which is more particularly designed for use in grain railway cars although the same may also be used in cars for carrying other kinds of loose or bulk freight.

The object of this invention is to provide a door of this character which is durable and not liable to become disarranged while in use, which can be easily shifted into its operative or inoperative position, and which is so constructed that the fastening devices of the relief section are relieved from the pressure of the grain and opening of this section is made easier.

In the accompanying drawings consisting of 2 sheets: Figure 1 is a fragmentary side elevation of a car showing a door opening therein closed by my improved door. Fig. 2 is a fragmentary longitudinal section in line 2—2, Fig. 4, showing the means for holding the folded door in its inoperative position next to the roof of the car. Fig. 3 is a fragmentary vertical section taken in line 3—3, Fig. 1 and showing the door closed. Fig. 4 is a similar view showing the sections of the door folded and suspended out of the way next to the roof of the car. Fig. 5 is a fragmentary vertical section of the lower part of the car door and adjacent parts, showing the relief section swung outwardly into its open position for permitting the adjacent part of the cargo of grain to escape preparatory to opening the door fully. Fig. 6 is a fragmentary vertical transverse section, on an enlarged scale, in line 6—6, Fig. 1, and showing the locking device for holding the central part of the relief section in its closed position. Fig. 7 is a fragmentary vertical longitudinal section taken in line 7—7, Fig. 3.

Similar letters of reference indicate corresponding parts throughout the several views.

A represents one of the side walls of a grain or similar railway car which has a door opening B, C the floor and D the roof of the same.

My improved door for closing the opening or door-way of the car consists essentially of an upper or filling section E, a central or intermediate section F and a lower or relief section G. The intermediate section is secured at its opposite vertical edges to the lower ends of a pair of hangers I which are pivoted at their upper ends adjacent to the inner side of the car body adjacent to the

roof, as shown at i, so as to permit of swinging these 50 hangers and the parts mounted thereon in a vertical plane. These hangers are preferably constructed of angle iron and arranged to bear in the closed position of the door with their transverse flanges i¹ against the faces of the stiles b and with their longitudinal flanges 55 i² against the inner sides of these stiles. For the purpose of stiffening the intermediate section of the door, the upper and lower edges of the same are provided with outwardly-projecting longitudinal flanges f, f¹, as shown in Figs. 1, 3 and 4.

The upper section of the door is normally arranged vertically between the hangers I and laps with its lower edge against the inner side of the upper edge of the intermediate section, so as to form a practically tight joint between the same, as shown in Fig. 3. At 60 its opposite vertical edges the upper door section is provided with outwardly-projecting vertical flanges e which are pivoted at their lower ends to the transverse flanges of the hangers by rivets e¹, as shown, or by any other suitable means. While the car is loaded, the 65 upper door section is held in an upright position by means of fastenings which connect the upper portions of its vertical flanges with the transverse flanges of the hangers, but when the car is to be loaded with grain or similar material, the upper door section is swung 70 outwardly at its upper end into the position shown by dotted lines in Fig. 3, so as to permit of introducing a spout into the car whereby the grain or similar material is delivered into the interior thereof. The means shown in the drawings, as an example, for holding the 75 upper door section in its operative position, consists of two horizontally sliding locking-bolts J mounted in brackets or guide-ways j on the upper part of the upper door section and each adapted to engage with a corresponding pair of openings or sockets k, k¹ in the adjacent vertical flanges of said section and the corresponding hanger, as shown in Fig. 1. For the purpose of stiffening this upper door section and enable the same to more effectually resist the outward thrust of the grain which is pressing against the inner side of the 80 same, a horizontal inwardly-projecting flange l is arranged at the upper edge of this section, as shown in Figs. 3 and 4.

The lower section of the door is arranged within a U-shaped frame which is preferably constructed of angle iron and comprises a lower horizontal bar having a vertical flange m and a longitudinal flange m¹ projecting outwardly from the upper edge of the vertical

flange, and two upright side bars each of which has a longitudinal flange n adapted to bear against the inner side of one of the door-frame stiles and a transverse flange n^1 projecting outwardly from the inner edge of the flange n and arranged along the face of the adjacent stile. The upper ends of the transverse flanges n^1 of the side bars extend a short distance above their companion longitudinal flanges and are pivoted to the inner sides and lower ends of the transverse flanges of the hangers I, as shown at o, so that the U-shaped frame is capable of swinging in a vertical plane and permit of folding the same together with the parts mounted thereon upwardly against the outer side of the intermediate and upper sections of the door. Inasmuch as the longitudinal flanges n of the side bars bear against the inner sides of the door-frame stiles in the closed position of the door, the same is held against outward displacement by the pressure of the grain within the car.

The lower or relief section G is provided at its opposite vertical edges with outwardly-projecting vertical flanges p which are pivoted at their upper ends by means of longitudinal rivets or pins P to the upper part of the transverse flanges of the side bars, so as to permit the lower end of this lower door section to be swung outwardly and upwardly, as shown in full lines in Fig. 5. At its lower edge the lower door section is provided with a longitudinal outwardly projecting flange q which is adapted to engage with the outwardly-projecting flange m^1 of the lower frame-bar, while the upper edge of the lower door section in its closed position is adapted to engage with the inner side of the lower part of the intermediate door section and form a tight joint between the same, as shown in Fig. 3.

While the grain door is in use the lower section is held in its closed vertical position by means of a locking or holding device, as shown in full lines in Fig. 3. Various means may be employed for holding the lower section in its closed position. As shown in Fig. 1, the opposite ends of the lower section are held in place by horizontal sliding bolts R which are guided in guideways or brackets r on said section and engage with corresponding openings r^1, r^2 formed in the adjacent transverse flanges of the lower section and the side bars of the U-shaped frame.

45 The fastening whereby the central part of the lower section is secured to the horizontal bar of the U-shaped frame consists of a flat stud S projecting outwardly from the lower part of this section, an upright coupling bar T pivoted at its lower end to an eye t on the vertical flange m and provided at its upper end with a slot u which is adapted to receive said stud, and a locking cam v pivoted at the upper end of the bar T and adapted to be moved by a handle V into and out of engagement with a notch s in said stud.

55 Upon releasing the lower door section the pressure of the grain against the inner side of the same pushes it outwardly, thereby permitting the grain in the immediate vicinity of the door to escape and thus relieve the pressure against the door so as to permit of opening the same fully with greater ease. In order to relieve the pressure or strain on the locking devices which hold the lower door section in its closed position, the coöperating longitudinal-transverse flanges q, m^1 of the lower section and the frame in which the same is mounted

are both inclined so that they rise toward their outer ends, as best shown in Figs. 3 and 6. By this means coöperating shoulders are formed on these parts whereby the outward thrust of the grain against the lower section at the lower end thereof is transmitted by its horizontal flange q against the opposing flange m^1 of the frame, thereby relieving the fastening devices from some of the pressure and enabling the same not only to be released more easily but also avoiding straining the same and possibly rendering the same inoperative. Inasmuch as the coöperating inclined shoulders of the U-shaped frame and the lower door section formed by the flanges q, m^1 prevent this door section from swinging outwardly while in its lowermost position, means are provided to permit this door section to rise bodily so that its flange or shoulder q may clear the opposing flange m^1 of the U-shaped frame and enable this door-section to swing outwardly. The preferred means for effecting this purpose consists in constructing the openings w in the flange p which receive the pivots P in the form of upright slots, as shown in Figs. 3 and 7. These slots are of sufficient length to permit the requisite vertical movement of the lower door section in the frame for clearing its lower end from the corresponding part of said frame. This lifting movement of the lower door section is effected automatically by the pressure of the grain against the inner side of the same which causes the lower door section to rise as its lower flange q rides upwardly on the flange m^1 of the frame until it clears the same.

In order to produce a tight joint between the lower bar of the U-shaped frame and the floor of the car, an L-shaped packing strip x is secured to this bar so as to bear against the floor in the closed position of the door, as shown in Figs. 3 and 5.

After the pressure of the grain in the immediate vicinity of the doorway has been relieved by the opening of the lower door section, the latter together with its frame are folded upwardly against the outer side of the intermediate and upper sections and while in this relative position the several sections together are swung on the pivots i inwardly and upwardly close to the roof of the car where they are retained in a suspended position by a supporting bail or retainer. This bail or retainer preferably consists of a horizontal longitudinal bar y adapted to engage with the underside of the lower door section and two upright arms y^1, y^2 projecting upwardly from opposite ends of the longitudinal bar and pivoted at their upper ends to the underside of the car roof or top so as to be capable of swinging in the vertical plane. Preparatory to folding and suspending the door next to the roof of the car, the supporting bail is swung inwardly so that the folded door will clear the same upon being moved to its highest position after which the bail is swung with its horizontal bar underneath the folded door and thus supports the same.

I claim as my invention:

1. A railway car door comprising an intermediate section, hangers connected at their lower ends with opposite vertical edges of said intermediate section and pivoted at their upper ends on the car body, an upper section pivoted at its lower end on said hangers, means for detachably connecting the upper part of said upper section with said hangers, and a lower section pivotally connected with said intermediate section, substantially as set forth.

2. A railway car door comprising an intermediate section, hangers connected at their lower ends with opposite vertical edges of said intermediate section and pivoted at their upper ends on the car body, an upper section pivoted at its lower end on said hangers, means for detachably connecting the upper part of said upper section with said hangers, a U-shaped frame having a lower horizontal bar adapted to be arranged at the floor of the car and two upright side bars which are connected at their lower ends with the horizontal bar while their upper ends are pivoted

to the lower ends of said hangers, a lower section pivoted at its upper end on said side bars, and means for detachably connecting the lower end of said lower section with the lower part of said frame, substantially as set forth.

Witness my hand this 22nd day of January, 1907.

OSCAR TOWER.
